UNITED STATES PATENT OFFICE

120,837

DESIGN FOR A REDINGOTE

Syd Novak, Chicago, Ill.

Application April 25, 1940, Serial No. 91,935

Term of patent 3½ years

To all whom it may concern:

Be it known that I, Syd Novak, a citizen of the United States of America, residing in the city of Chicago, county of Cook, and State of Illinois, have invented a new, original, and ornamental Design for a Redingote, of which the following is a specification, reference being had to the accompanying drawing, forming part thereof.

Fig. 1 is a front view of a redingote showing my new design.

Fig. 2 is a rear view thereof.

I claim:

The ornamental design for a redingote substantially as shown.

SYD NOVAK.
